Des. 185,734
Patented July 28, 1959

185,734

VAGINAL MEDICATOR

Gaston Chappaz and Jean Boës, Paris, France
Application January 27, 1958, Serial No. 49,411

Term of patent 14 years

(Cl. D83—1)

Fig. 1 is a side elevational view of a vaginal medicator showing our new design.

Fig. 2 is a top plan view.

Fig. 3 is a bottom plan view.

Fig. 4 is a right side elevational view thereof.

We claim:

The ornamental design for a vaginal medicator, as shown.
